ORNAMENTAL FABRIC AND ARTICLES
MADE THEREFROM

Samuel La Fair, Philadelphia, Pa.

Application June 15, 1946, Serial No. 676,996

5 Claims. (Cl. 154—47)

1

This invention relates to ornamental fabrics and to articles made therefrom. The principal field of usefulness of the fabric is in the making of ornamental articles, blanked out of the fabric in various designs, and adapted to be applied to women's dresses, hats and other articles of wearing apparel for the purpose of ornamenting the same.

The principal object of the present invention is to provide an ornamental fabric of peculiar, novel and attractive appearance, which may be used for a variety of purposes, but which is particularly adapted for blanking out in fanciful patterns, such as butterflies, leaves, medallions, etc., which may be applied to various garments for the purpose of attractively decorating the same.

A further object of the invention is to provide an inexpensive ornamental article of desired shape, adapted to be applied to garments and the like, which will have the appearance of having a plurality of spaced jewels mounted thereon.

The nature and characteristic features of the invention will be more readily understood from the following description taken in connection with the accompanying drawing forming part hereof, in which:

Figure 1 is a top or plan view of an ornamental fabric embodying the main features of the present invention, the same being shown broken away to illustrate the several layers thereof, and to illustrate the method of making the fabric;

Fig. 2 is an enlarged cross section of a portion of the fabric; and

Fig. 3 is a plan view of a typical ornamental figure, blanked from the fabric to be applied to a garment or other wearing apparel to decorate the same.

It should, of course, be understood that the description and drawing herein are illustrative merely, and that various changes and modifications may be made in the structure disclosed without departing from the spirit of the invention.

Referring to the drawing, in the particular embodiment of the invention therein shown, 5 is a foundation fabric which, as shown, may preferably comprise a woven textile cloth, but any strong tough sheet material may be employed for the foundation, if desired, such as paper, Cellophane, or the like.

Upon one face of the foundation fabric 5 there is applied a coating of suitable adhesive 6, which is also may be of any preferred kind, such as lead plaster, a latex compound, or one of the ad-

2

hesives 5 used for the pressure sensitive permanently tacky coatings used on the so-called "Scotch tape." Preferably a type of adhesive is used which will remain tacky for sometime after being applied to the foundation fabric so that there will be no necessity of haste in the subsequent steps in the process of making the completed fabric.

Upon the adhesively coated side of the foundation fabric 5 there is mounted a sheet 7 of suitable material provided with a plurality of closely located spaced apertures 8. The apertures 8 may be of any desired shape, but it has been found in practice that the material from which 15 sequins have been previously punched, is a satisfactory perforated material for the present purpose.

This sheet 7 of perforated material which is preferably employed consists of a sheet of transparent resinous plastic, which may be plated on one side with a thin metallic coating for the purpose of providing a proper luster to the material, but this is not absolutely essential. If desired, a thin sheet metal may be used for this purpose 20 in which event it may be necessary in some instances to lacquer the exposed surface to prevent subsequent dulling thereof.

After the perforated sheet 7 is mounted on the adhesive coating 6 of the foundation fabric 5, 30 the assembled sheets are then dusted with flaked tinsel 9, the particles of which will adhere to the adhesive 6 which is exposed through the perforations of perforated sheet 7 so that there will be provided a multiplicity of small spaced fields, 35 each of which is covered by a mass of flake tinsel held in place by the adhesive coating which is disposed within the respective perforations of the sheet 7.

After the fabric is made as aforesaid, the 40 ornamental articles which are made from the same may be punched or blanked out of the completed fabric, as, for example, the form 10 shown in Fig. 3 which illustrates the utilization 45 of the fabric in an appliqued design. The article shown in Fig. 3, when applied to a garment or other piece of wearing apparel, will constitute an attractive and desirable ornament having the appearance of a jewelled design.

50 I claim:

1. An ornamental fabric comprising a foundation sheet having a pressure sensitive adhesive on one face thereof to which is secured by said adhesive a sheet of plastic material having a plurality 55 of perforations, and particles of tinsel disposed

in said perforations and held therein by said adhesive.

2. An ornamental fabric comprising a foundation sheet having one face thereof coated with an adhesive, a sheet of material secured to said foundation sheet by said adhesive and having a plurality of regularly spaced perforations, and particles of light reflecting material disposed in said perforations and held therein by said adhesive.

3. An ornamental fabric comprising a foundation sheet having one face thereof coated with a pressure sensitive adhesive, a sheet of material secured to said foundation sheet by said adhesive and having a plurality of regularly spaced perforations, and particles of tinsel disposed in said perforations and held therein by said adhesive.

4. An ornamental article blanked in desired shape from a fabric comprising a foundation sheet having one face thereof coated with an adhesive, a sheet of material secured to said foundation sheet by said adhesive and having a plurality of regularly spaced perforations, and particles of light reflecting material disposed in

said perforations and held therein by said adhesive.

5. An ornamental article blanked in desired shape from a fabric comprising a foundation sheet having one face thereof coated with a pressure sensitive adhesive, a sheet of material secured to said foundation sheet by said adhesive and having a plurality of regularly spaced perforations, and particles of tinsel disposed in said

10 perforations and held therein by said adhesive.

SAMUEL LA FAIR.
